WOODEN AGING BARREL

Frank M. Shipman, Louisville, Ky.

Application November 18, 1939, Serial No. 305,065

2 Claims. (Cl. 217—80)

This invention relates to wooden whisky aging barrels, i. e. barrels of the character employed for aging spirituous liquors such as whiskey. During the manufacture of such barrels, the heads are fabricated to size and shape, machined to provide the bead and bevels, charred on one side and thereafter cooled and stored for use as needed, while the cylinder, after being initially formed and hooped, is charred on the inside and then machined to provide the howels, crozes and chimes. The ends of the cylinder are then closed by the heads and additional hoops provided to tighten the cylinder around the heads and thus complete the manufacture of the barrel. Since the closing and tightening operations are performed while the cylinder is still hot from the charring operation, the "char" heat causes the air within the barrel to expand, normally creating a "char" pressure of 6 to 8 pounds.

Despite the tightness of the barrel, considerable loss of whiskey is occasioned, during aging, by evaporation, leakage and the like. This loss, or "outage" as it is usually called, approximates as much as 20% of the initial contents of the barrel during an aging period of four years. That portion of the overall outage, which occurs around the end joint where the bead of the head fits into the croze of the cylinder, is herein designated "end-joint outage." It is occasioned primarily by the leakage of whiskey through crevices and cracks in the wood at the end joint, and secondarily by the seepage and diffusion of whiskey and its vapors through the pores and along the grain of the wood around the end joint. Since end-joint outage approximates as much as one-fifth of the overall outage, attempts have heretofore been made to eliminate it by coating the outer bevel of the head and the outer howel and chimes of the cylinder with various sealers but they have not been entirely satisfactory.

I have discovered that end-joint outage may be substantially reduced, if not entirely eliminated, by providing a suitable sealer on the inside of the barrel and causing such sealer to penetrate and seal the cracks, crevices and pores of the wood forming the inner-joint surface, i. e., the bead and inner-bevel surfaces of the head and the croze and inner-howel surfaces of the cylinder, and such forms the principal object of my invention.

Another important object of the invention is to provide a novel method of sealing a wooden aging barrel against end-joint outage, which method can be practised during, and as an incident of, the regular barrel-manufacturing

process without complicating such process or materially increasing its expense.

A further object is to provide a sealing method which utilizes the "char" heat and pressure to effect the penetration of a previously applied sealer.

The invention is illustrated in the accompanying drawing, wherein:

Figure 1 is a fragmentary section of the head of a wooden aging barrel;

Figure 2 is a fragmentary section of one end of a barrel cylinder; and

Figure 3 is a fragmentary section showing the relation of the head and cylinder with the invention applied.

The invention is illustrated as applied to one end of a wooden aging barrel which is conventional in that it comprises the usual head 1, having outer and inner bevels 2 and 3 terminating in a peripheral bead 4, and cylinder 5, having a chime 6 and outer and inner howels 7 and 8 separated by a croze 9. So far as the present invention is concerned, these parts may be manufactured and assembled in the conventional way.

When assembled, the bead of the head fits within the croze of the cylinder to form the end joint of the barrel. The term "inner-joint surface," as hereinafter used, designates the bead and inner-bevel surfaces of the head and the croze and inner-howel surfaces of the cylinder.

In accordance with the present invention, a suitable sealing material is applied to all or a suitable portion of the inner-joint surface, prior to the assembly of the barrel, and upon assembly, the sealer is subjected to a pressure within the barrel which forces it to penetrate and fill the cracks, crevices and pores of the wood forming the inner-joint surface and thereby effectively seal the barrel against end-joint outage.

While any of a variety of well-known sealing materials, which do not react unfavorably with whiskey, may be employed, the use is preferred of a normally solid impervious sealer, having a low melting point, i. e. a melting point below the "char" heat temperatures normally encountered during the manufacturing process but above the barrel and whiskey temperatures normally encountered during the aging process. A wax, such as paraffin, appears to be ideally suited for use as a sealer in the practice of the present invention. Various resins and resinous substances may also be employed.

While the sealer may be applied to all or a suitable portion of the inner-joint surface in any

desired way, it is only necessary to apply it to the head, and such application is preferred because of the ease and rapidity with which it may be accomplished. For example, when the head is completely formed, it may be rolled through a shallow layer of molten paraffin (not shown) in a tilted manner such as to coat the bead 4 and part or all of the inner bevel 3. Upon hardening, the wax will form a thin solid film 10 as indicated in Figure 1.

When a coated head is assembled into a barrel, the cylinder of which is cold, it will be necessary to apply sufficient heat to melt the sealer and, upon melting and subsequent hardening, an effective seal will result. The seal, however, may be greatly improved by creating a pressure within the barrel while the sealer is in a liquid condition so as to cause the sealer to penetrate the crevices, cracks and pores of the inner-joint surface before hardening. In this way, the sealer extends from the inner-joint surface into the openings of the wood forming such surface in a pressure-packed condition. In the usual barrel manufacturing process, where the barrel parts are assembled while the cylinder is still hot from the charring operation, the "char" heat and pressure will ordinarily be amply sufficient to effect the melting of the sealer and its penetration into the inner-joint surface. The normal surface distribution of the sealer and the normal depth and area of its penetration into the wood is indicated by the shading 10a in Figure 3. Where, however, the head and cylinder contain one or more large pores or crevices, as indicated at 10 and 11, which extend through or into the normal penetration area, the sealer will usually flow into and along such pores and crevices to an appreciable degree. In fact, sealer excrescences have been observed on the outer bevel of the head and the chimes of the cylinder indicating that the "char" pressure has forced the sealer along some particular path completely through the full thickness of the wood. If the "char" pressure is insufficient or lost, it should be sup-

plemented or replaced by gas or air pressure supplied from any suitable outside source.

As the barrel cools, the sealer hardens ultimately resulting in a solid impervious seal which 5 not only fills the cracks and crevices of the inner-joint surface but extends well into the pores and along the grain of the wood. As will be evident, a seal of this character will substantially reduce, if not entirely prevent, the escape of whiskey or 10 its vapors through the area embraced by the seal and thus practically eliminate end-joint outage. It will also be evident that the cost of applying the seal is negligible, while the mode of application does not interfere with or complicate 15 routine manufacturing practice.

Having described my invention, I claim:

1. An improvement in the process of manufacturing wooden whiskey aging barrels having an inner joint surface where a head is jointed into 20 the cylinder comprising: applying a normally solid sealer having a low melting point to the inner-joint surface of the heads before they are jointed into the cylinder; and, after the heads are jointed into the cylinder, subjecting the 25 sealer to heated fluid under pressure, the heat being of an order sufficient to melt the sealer and the pressure being of an order sufficient to force the melted sealer into said inner-joint surface.
- 30 2. An improvement in a wooden whiskey aging barrel manufacturing process wherein "char" heat and pressure are created within the barrel when the heads, having inner-joint surfaces, are jointed into the cylinder while the latter remains 35 hot from the charring operation, comprising: coating the inner-joint surfaces of the heads, before the jointing operation, with a normally solid impervious sealer, having a melting point below the "char" heat temperature, whereby the 40 "char" heat is sufficient to melt the sealer and the "char" pressure is sufficient to force the melted sealer into said inner-joint surface.
